(57) **CLAIM**

The ornamental design for a programmer for a therapeutic medical device, as shown and described.

DESCRIPTION

FIG. 1 is a top perspective view of a programmer for a therapeutic medical device, showing our new design;

FIG. 2 is a bottom view thereof;

FIG. 3 is a bottom view thereof, with an attachment removed;

FIG. 4 is a right side view thereof;

FIG. 5 is an end view thereof;

FIG. 6 is a top view thereof;

FIG. 7 is an end view thereof, opposite that shown in FIG. 5;

FIG. 8 is a left side view thereof;

FIG. 9 is top perspective view thereof;

FIG. 10 is another top perspective view thereof; and,

FIG. 11 is a bottom perspective view thereof.

The broken lines shown in FIGS. 1-11 are for illustrative purposes only and form no part of the claimed design.
